UNITED STATES PATENT OFFICE.

FELIX H. CRAGO, OF HOT SPRINGS, MONTANA.

ROTARY WATER-MOTOR OR PUMP.

Specification of Letters Patent. Patented June 21, 1921.

1,382,065.

Application filed September 25, 1919. Serial No. 326,190.

To all whom it may concern:

Be it known that I, FELIX H. CRAGO, a citizen of the United States, residing at Hot Springs, in the county of Sanders and State of Montana, have invented a new and useful Rotary Water-Motor or Pump, of which the following is a specification.

My invention relates to new and useful improvements in rotary water motors which 10 may be employed as a pump, and an important object of the invention is to provide a device of this nature including a stator having journaled therein a rotor and rotary member, the axis of the rotor being arranged 15 above the axis of the rotary member between the intake and the discharge ports of the stator to insure non-leakage in the stator.

Another object of the invention is to provide a device including a stator having a 20 rotor and rotary member journaled therein upon relatively offset axes, and in which is embodied means whereby a blade carried by the rotor has at all times the proper axially offset relation to the stator.

25 A still further object of the invention is to provide simple and efficient means to compensate for wear imposed upon several parts of the motor.

Other objects and advantages of the invention will become apparent during the 30 course of the following description.

With the above and other objects in view, which will appear as the description proceeds, the invention resides in the combination and arrangement of parts and the details of construction hereinafter described and claimed, it being understood that, within the scope of what is claimed, changes in the precise embodiment of the invention 35 shown can be made without departing from the spirit of the invention.

In the accompanying drawings, forming a part of the description and wherein like numerals are employed to designate like 40 parts throughout the several views.

Figure 1 is a sectional view disclosing a motor embodying the invention, the cutting plane being coincident with the axis of rotation of the rotor, parts remaining in elevation;

Fig. 2 is a vertical section taken on line 2-2 of Fig. 1; and

Fig. 3 is a vertical section taken on line 3-3 of Fig. 1.

55 In the drawing, wherein for the purpose of illustration is shown a preferred embodiment of the invention, the numeral 4 designates the stator, in general, which consists of a side plate 5, equipped with a depending portion 6 terminating in a base 7, from which extends an upright standard 8, the upper end of which is provided with a bearing 9 having the usual oil cup mounted thereon.

The inner face of the side plate 5 is provided adjacent its top with a recess 11 from which extends a second recess 12 smaller in diameter than the recess 11. A hub 13 is provided upon the side plate 5 and closes the recess 12 at its outer end. A shaft 14 is journaled on the hub and in the bearing 9. A bushing 15 is retained within the hub and receives the shaft 14 for rotation.

A rotor 16 is journaled in the recess 11 and is provided with a boss 17 journaled in the recess. The shaft 14 is secured to the 75 rotor by a cross-pin 18, mounted in the boss 17 and held therein by the outstanding part of the plate 5 wherein the recess 12 is located.

As shown in Fig. 2, the top 19 of the stator 80 has its interior surface provided with an arcuate recess 20, which is arranged between the discharge and intake ports 21 and 22 respectively. The periphery of the rotor engages the arcuate recess 20 for a purpose 85 which will appear hereinafter.

As shown in Fig. 2, the rotor is equipped with a diametrically extending slot 23, the walls of which carry expandable facings 24 held in proper position by retaining bolts 25.

A blade 26 is slidably mounted in the slot 23 of the rotor between the facings 24 and is retained therein through the medium of a pin 27 extending through a bushing 28 in the blade. This pin 27 is carried by a rotary member 29, in a form of a disk, the pin being mounted on the disk adjacent the periphery thereof. The relative outer face of the rotary member 29 is equipped with an annular rib 30 arranged adjacent the edge 95 of the disk and a pin 31 extends transversely through the pin 27 and into the rib 30 to retain the pin 27 on rotary member 29.

An annular recess 32 provided in the inner surface of a face plate 33 receives the rib 105 30. This face plate 33 is equipped with lugs 34 which coöperate with similarly arranged lugs on the stator, the face plate being secured to the stator by bolts 35 located in the lugs.

The rotary member or disk 29 is of the same diameters as the interior of the stator,

and is mounted within a recess 36 in the inner face of the face plate 33.

A shaft 37 is secured to the center of the disk 39 and extends through a bushing 38 provided in a hub 39 formed upon the outer face of the face plate 33. The bushing 38 abuts at one end against the rotary member 29 and at its other end against a screw 40 which provides means to compensate for wear upon the rotor, blade, disk, and associated parts. A lock-nut 41 is threaded upon the screw 40 to retain the same and consequently the bushing 38 in the desired position.

15 It will be apparent that the rotor and the rotary member are journaled in the stator upon relatively offset axes. Therefore when the device is used as a water motor and the water enters the stator through the inlet 20 port, the water will exert a pressure upon the portion of the blade 26 which projects beyond the periphery of the rotor. Due to the fact that the blade is carried by the rotary member 29 adjacent the periphery thereof, 25 it will be seen that the blade will slide in the slot 23 of the rotor and at the same time will cause rotation of the rotor, rotary movement being imparted to the shaft 14. Should either the rotary member 29 or any other 30 associated parts become worn, the screw 40 may be adjusted to move the bushing 38 and the member 29 inwardly thereby to compensate for wear upon the worn parts.

The shaft 14 is so located that the periphery of the rotor 16 is held in engagement with the recess 20, and, consequently, leakage between the inlet port and the outlet port 21 will be prevented.

Having thus described my invention what 40 is claimed is:

1. In a device of the class described, a stator; a rotor and a plate at one end of the rotor, the rotor and the plate being journaled on different axes, the rotor being in contact 45 throughout a portion of its periphery with the inner curve of the stator, the plate being of larger diameter than the rotor; a blade mounted for right line reciprocation in the rotor and co-operating at its outer end 50 with the inner curve of the stator; and a con-

necting element carried by the plate adjacent to the periphery thereof, the connecting element being mounted to rock in the blade.

2. A device of the class described, constructed as set forth in claim 1, and further characterized by the fact that there is an annular recess in one side of the stator, the plate having an outstanding annular rib rotatable in the recess, the connecting element being mounted in the rib.

3. A device of the class described, constructed as set forth in claim 1, and further characterized by the fact that there is an annular recess in one side of the stator, the plate having an outstanding annular rib rotatable in the recess, the connecting element being mounted in the rib; and a securing device passing through the connecting element and mounted in the rib, the connecting element being held by engagement with the 65 stator, against endwise displacement.

4. A device of the class described, constructed as set forth in claim 1, and further characterized by the fact that the stator has an outstanding hub, the plate being carried 75 by a shaft extended into the hub; a bushing about the shaft and housed in the hub, the inner end of the bushing engaging the plate; and an adjusting element mounted in the hub and co-operating with the bushing, independently of the shaft, to advance the bushing and the plate.

5. A device of the class described, constructed as set forth in claim 1, and further characterized by the fact that the rotor 85 has an outstanding hub, the stator having a recess wherein the hub is journaled; a shaft journaled in the stator and extended into the hub; and a securing element passing through the hub and the shaft, the securing element being held against endwise displacement by that portion of the stator in which the recess is located.

In testimony that I claim the foregoing as my own, I have hereto affixed my signature in the presence of two witnesses.

FELIX H. CRAGO.
